Patented Sept. 9, 1919.

UNITED STATES PATENT OFFICE.

ERNEST B. COBB, OF JERSEY CITY, NEW JERSEY, ASSIGNOR TO STANDARD OIL COMPANY, A CORPORATION OF NEW JERSEY.

PROCESS FOR THE TREATMENT OF PETROLEUM-OILS.

1,315,623.

Specification of Letters Patent.

Patented Sept. 9, 1919.

Application filed August 2, 1917. Serial No. 184,072.

To all whom it may concern:

Be it known that I, ERNEST B. COBB, a citizen of the United States, residing at Jersey City, in the county of Hudson and State of New Jersey, have invented certain new and useful Improvements in Processes for the Treatment of Petroleum-Oils, of which the following is a specification.

My invention relates to new and useful improvements in processes for the treatment of petroleum oils, and particularly contemplates a process for purifying and decolorizing petroleum oils which have been subjected to treatment with sulfuric acid, for the purpose of removing from such oils reaction products such as sulfo-acids resulting from such acid treatment.

It is well known that petroleum oils have been treated with commercial sulfuric acid, *i. e.*, of 66° Baumé strength for the purposes of purification, and afterward either alkalinating or neutralizing the oil so treated with soda or other suitable neutralizer, for the purpose of removing the acid and reaction products. This treatment, however, is not satisfactory where extreme degrees of purity are desired, because the finished oil contained sulfo-acids which could not be removed by the well-known methods of treating with alkali.

My invention particularly contemplates a process which will effectually remove practically all of the sulfo-acid products which remain after the sulfuric acid and alkali treatment, and, therefore, make my improved process available for producing oils which may be effectually treated to produce a product which is practically colorless and void of odor.

The invention consists in the improved process to be more fully described herein-after and the novelty of which will be particularly pointed out and distinctly claimed.

In order that the various steps of the process will be readily understood by those skilled in the art, I have illustrated in the accompanying drawings one form of apparatus which may be employed with advantage to perform the process.

Before describing in detail the preferred method of carrying out the process, as regards the ingredients, quantities thereof, temperatures and steps employed, I would state the process briefly, as follows: I take a petroleum oil, such, for instance, as is to be employed for the production of an oil of a high degree of purity employed for medicinal purposes, and treat the same with a proper amount of sulfuric acid for the purpose of removing the color, and those elements producing odor, employing for this purpose sulfuric acid of high strength—for instance, containing 20% of sulfuric anhydrid (SO_3) which is 104½% oleum—that is, it is an acid not only containing no excess free water but one which consists of the mono-hydrate with the sulfuric anhydrid in solution, and, therefore, of great strength, far beyond that hitherto usually employed in the acid treatment of petroleum oil. Other strengths of acid are not necessarily excluded if the character of the oil and the results desired permit.

This acid treatment may be repeated as often as may be desired in order to produce the required degree of purification, the oil being permitted to cool between applications of the acid in order to prevent rapid evolution of gas—sulfurous acid gas due to the chemical reaction, which might result in destruction or alteration of the oils, the character of which it is desired to retain unchanged. After each application of the oil the resulting sludge is drawn off and the supernatant oil is then subjected to the succeeding application of the acid if further application is necessary. When the desired number of applications of the acid have been made, the oil is permitted to stand so that the sludge may settle, which may require anywhere from ten to forty-eight hours. The sludge is then drawn off and the supernatant oil is transferred to a clean vessel and alkalinized with soda-ash, sal-soda, or caustic soda in solution, or any other ingredient suitable in oil treatment for neutralizing the acids—for example, potash and ammonia. The action of the alkali is to

neutralize the free acid and also the sulfo-acids resulting from the reaction between the acid and the oil, and in certain types of oils, for instance, those from Texas crude, 5 will neutralize the natural acids therein. This alkali is added in an amount in excess of that required for neutralization, such as generally contemplated, and may be from 10° to 40° Baumé solution in the case of 10 caustic soda, for example. I employ alkali of great strength, and a large quantity thereof in order that the supernatant oil resulting after the alkali treatment will be practically emulsion-free, the alkali acting 15 to render the oil and the alkali solution as little soluble as possible in each other, and thereby effecting a distinct separation. After the alkali treatment the bottom layer containing the excess alkali, and the neutralized sulfuric acid in solution in the bulk of the water are drawn off, leaving the upper layer of oil containing sulfo-acid salts in solution.

The usual method which would be followed at this point would be to wash the 25 oils with water, but this cannot be done for the purpose of removing the sulfo-acid salts because the addition of the water for washing would result in an emulsion being 30 formed between the water and the sulfo-acid salts which are soluble partly in the water and partly in the oil, which would result in some of the sulfo-acid salts still remaining in the oil, and a permanent emulsion which it would be practically impossible to remove.

In order to effectually remove substantially all, if not all, of the sulfo-acid salts I treat the oil containing these acid salts as 40 follows:

The oil is treated by any suitable or well known step, for instance, blowing with air to remove water therefrom preferably as much as possible. When the alkali is withdrawn the oil may contain as much as 5% water, and I endeavor to remove as much of this water as possible. The oil is then subjected to glycerin ($C_3H_5(OH)_3$) which is thoroughly mixed therewith so as to effectually bring the glycerin in contact with all parts of the body of the oil, which glycerin forms a solution of the sulfo-acid salts, but will not go into solution with the oil, except to a very small extent, if at all. This glycerin should be as water-free as possible. I have ascertained that commercial glycerin, which is 96% pure, will effectually obtain the desired results, but I do not limit myself to glycerin of this high degree of purity as 55 strengths as low as 90% have been found satisfactory, although strengths as low as 80% will not produce satisfactory results. After the glycerin treatment the treated oil is permitted to stand until it separates into

two distinct layers, which may require 65 twenty-four hours. The lower layer will contain glycerin and the sulfo-acid salts in solution in glycerin, while the upper layer will be a hydrocarbon oil free from sulfo-acid salts. This oil may then be washed and 70 filtered, whereupon it will be inodorous and practically colorless, and in which there will be no tendency to emulsify when submitted to the washing process. During the settling, after the glycerin treatment, the oil may be, 75 and preferably is, maintained at a suitable temperature, say about 170° F., to hasten the settling process, which might take unnecessarily long, due to the viscous nature of the cold glycerin and the oil.

Having now described generally the process I will set forth in detail one example of performing the same, the same being described in connection with the apparatus shown in the accompanying drawing.

The desired oil which has been previously treated with the sulfuric acid of great strength is flowed through a pipe 1 into a covered tank or receptacle 2. As heretofore stated, the oil may be of any type which it is desired to purify, for example, an oil of 400 viscosity at a temperature of 100° F. on the Saybolt universal viscosimeter, although I do not confine myself to such an oil, as the process is of value in treatment of any viscous oil in which there is liability to the formation of emulsions when subjected to acid and alkali, for instance, an oil as low as 75 viscosity. In the previous treatment of the oil with sulfuric acid, the acid of the 100 strength and character heretofore described is used in proportion of about 37% by volume of the oil being treated. As a preliminary, I may treat the oil with 66° Baumé sulfuric acid to remove a large proportion 105 of the impurities which may be contained in the oil when it comes from the still, as a matter of economy in the use of acid. The desired quantity of settled oil is run into the tank 2, and an alkali solution consisting of 110 soda or sal-soda or other suitable alkaline substance, as heretofore mentioned, but preferably caustic soda, is run into the tank through an inlet pipe 3, this caustic soda solution being preferably from 10° to 40° 115 Baumé. I preferably employ a strength of about 10° Baumé for purposes of economy, but the stronger the solution used the more certain will be the separation. It will be understood that the strength of the alkali solution and the quantity thereof employed must be such that there will be a clear line of separation between the oil and the bottom layer or aqueous layer. In employing a 10° strength of caustic soda the volume would 120 be about 20% of the body of oil being treated. As soon as a proper separation has taken place, which may take from ten to 125

forty-eight hours, but which will be readily apparent upon examination of the oils by sampling, the bottom layer containing the neutralized acid, water and the excess of alkali which has not entered into combination, is drawn off through a pipe 4 leading from the bottom of the tank and connected to the pipe 5, the pipe 4 containing a control valve 6, and the pipe 5 having a control valve 7. When the bottom layer has been drawn off, the upper layer of oil containing traces of water, which may amount to 5% by volume, and practically all of the sulfo-acid salts resulting from the alkali treatment will remain in the tank, and the valves 6 and 7 are then closed. In order to remove the remaining traces of water which are in the body of oil, the latter is heated by a steam coil 8 in the bottom of the tank and controlled by inlet valve 9 and outlet valve 10, to a temperature of 200° F., or thereabout, this heating serving to assist in the removal of water when the oil is subjected to blowing with air admitted to the interior of the tank by a blow pipe 11, the lower or outlet end of which terminates adjacent the bottom of the tank so that the air will permeate the body of the oil. The top of the tank may be provided with an outlet vent 12 for the escape of steam and air. The heating and blowing is carried on until the escape from the vent pipe will cease to show water or steam, which can be determined by any of the well known means known by those skilled in the art.

The oil is then ready to be subjected to the glycerin, which is admitted to the interior of the tank 2 by an inlet pipe 13. This glycerin, as heretofore stated, may be of commercial strength, which is about 96%, the more water-free the glycerin is the better being the results obtained, although it may be 90%, as I have demonstrated. The glycerin is admitted to the tank in a quantity of about from 5% to 10% by volume of the body of oil being treated. I have found that a quantity in proportion of 8% of glycerin by volume will efficiently serve the purpose. The body of oil containing the glycerin is thoroughly agitated by any suitable means in order to thoroughly admix the glycerin with the oil and bring it in contact with all parts thereof. A blast of air through the pipe 11, heretofore described, will efficiently produce the desired agitation. This step of treatment of the oil with the glycerin, accompanied by agitation, might take an hour, but this time is not obligatory because the purpose is to produce a solution of the sulfo-acid salts, and a definite separation, and the time for doing this, can be readily determined by test samples, that is, samples may be taken from time to time and the step terminated when it is clear that

a definite separation takes place and the oil is free from sulfo-acid salts. When the treatment with glycerin is completed the body being treated is permitted to settle, which will result in the formation of two layers, the lower layer containing glycerin, sulfo-acid salts in solution in glycerin, and a comparatively small amount of oil, which may be soluble in the glycerin mixture. This settling process may be accelerated by heating by the steam coil 8, and will take from twenty-four to forty-eight hours, although the time stated is not essential as it may be readily determined by test when a proper separation has taken place. The upper layer produced from the settling will be the purified oil, free from sulfo-acid salts.

When the settling and separation is accomplished, the lower layer, heretofore described, is drawn off from the tank 2, through the pipe 4 and a pipe 14, discharging into a still 15 for treatment for the purpose of recovering the glycerin for further use. The pipe 14 is controlled by a valve 16. After the lower or bottom layer is drawn off the purified oil remains in the tank 2, and possibly small traces of glycerin mechanically adhering to the interior of the tank. In order to remove these traces of glycerin the purified oil may be washed by flowing water, say 5% by volume of the oil, into the tank through the pipe 3 and agitating by the air blast, after which by settling a bottom layer is formed containing the water and all the traces of glycerin not hitherto removed. This bottom layer may then be flowed through the pipes 4 and 14 into the still 15. The valve 16 may then be closed and the valves 6 and 7 opened, and the purified oil run out of the tank 2, or a separate outlet for the purified oil may be provided if desired. This purified oil may be further treated by washing after withdrawal from the tank 2, and finally filtered through any decolorizer which is suitable, for instance, fullers' earth or clay, whereupon the oil will be water-white, and in the case of a medicinal oil, be made satisfactory for use.

The alkali mixture and glycerin which is flowed into the still 15 may then be heated by a suitable furnace 17, preferably, up to a temperature of about 450° F., which will first serve to drive off the water, which will flow out of the dome 18 and through the pipe 19 to a coil 20 of a condenser 21, wherein the water will be condensed and flowed into one or the other of two receiving tanks 22, 23, connected respectively by inlet pipes 24, 25, with an outlet pipe 26 from the condenser coil, the pipes 24 and 25 being provided with hand valves 27, 28, respectively, and each of the said tanks 22 and 23 may be provided

with vents 29, 30, controlled by valves 31, 32, respectively. The water vapors initially driven off by heating, and which may contain some glycerin, will flow into the tank 22, which is the first on the condenser outlet line. When the water is driven off, glycerin and the sulfo-acid salts will remain in the still, the said salts being non-volatile at temperature conditions and pressures at 10 which glycerin is volatile, preferably under vacuum produced by a vacuum pump 33 connected by a pipe 34 to the condenser outlet pipe 26, which results in the glycerin being driven off as a vapor flowing through 15 the pipe 19 to the condenser coil, where it is condensed, and from which it emerges by the pipe 26 and passes to the receptacle 23. The distillation is carried on under vacuum or pressure as low as possible to prevent 20 decomposition of the glycerin. After the distillation has progressed until a small amount or trace thereof remains in the still, this remaining amount may be recovered by accelerating the distillation by means of 25 open steam admitted to the interior of the still through a supply pipe 35, having at its lower end a perforated outlet pipe 36. The steam may be used, if desired, throughout the distillation to accelerate the distillation. 30 The steam supply pipe 35 is provided with spaced hand valves 37, 38, between which is a valved outlet pipe 39, which latter may be employed as a water drain to remove water of condensation which might collect in the 35 steam supply pipe above the valve 38, so that this water will not be permitted to pass into the still. The tanks 22 and 23 are connected by outlet connections 40, 41, with a pipe 42 leading to a liquid pump 43 having 40 an outlet pipe 44 discharging into an open evaporator pan 45, the latter being heated in any suitable manner, as by closed steam coil 46, the inlet and outlet of which are controlled by hand valves 47, 48. The 45 evaporator pan is provided with a valved outlet 49 for removal, and each of the connections 40, 41 is provided respectively with hand valves 50, 51.

After the distillation of the glycerin is 50 completed the sulfo-acid salts remain in the still 15, from which they may be withdrawn by an outlet pipe 52 controlled by an internal valve plug 53 operable by a valve stem 54 and handle 55, said outlet 52 also 55 having an external valve 56. The condensed products which have passed over into the tanks 22 and 23 will consist of a mixture of water and glycerin in the tank 22, and the glycerin of a higher degree of 60 concentration in the tank 23. The products in the tanks 22 and 23, or either of them, may be withdrawn by the pump 43 and delivered into the evaporator pan 45, where, by heating by means of the steam coil 46, the

water may be evaporated and the glycerin 65 concentrated to the desired degree.

It will be apparent that the matter constituting the bottom layer after the glycerin treatment, which is run into the still, will be alkaline, and for this reason might 70 result in decomposition of some of the glycerin. In order to obviate loss of glycerin, which might result from such decomposition, I may add enough sulfuric acid to the mass in the still to make it neutral, and thereby 75 prevent loss, which is likely to occur were the strongly alkali mass alone subjected to the heat of the still.

By the term "sulfo-acid" as employed herein and in the claims, is meant those 80 products or acids which result from the action of the sulfuric acid upon certain hydrocarbons or elements of hydrocarbons contained in petroleum oil. By the term "sulfo-acid salts" as employed herein and 85 in the claims is meant the neutralization products which result from the action of alkali on the sulfo-acids.

What I claim and desire to secure by Letters Patent of the United States is: 90

1. The process of treating petroleum oils containing sulfo-acid salts, which consists in removing said salts from the oil by subjecting the oil to the action of glycerin.

2. The process of treating petroleum oils 95 containing sulfo-acid salts, which consists in removing said salts from the oil by subjecting the oil to the solvent action of glycerin.

3. The process of treating petroleum oils 10 containing sulfo-acid salts, which consists in removing said salts from the oil by subjecting the oil to the solvent action of glycerin accompanied by agitation.

4. The process of treating petroleum oils 10 containing sulfo-acid salts, which consists in removing said salts from the oil by subjecting the oil to the solvent action of glycerin accompanied by agitation and heat.

5. The process of treating petroleum oils 11 containing sulfo-acid salts, which consists in removing said salts from the oil by subjecting the oil to the solvent action of glycerin under conditions precluding the presence of a substantial amount of water. 11

6. The process of treating petroleum oils containing sulfo-acid salts, which consists in removing said salts from the oil by subjecting the oil to the solvent action of substantially water-free glycerin. 12

7. The process of treating petroleum oils containing sulfo-acid salts, which consists in removing said salts from the oil by subjecting the oil to the solvent action of glycerin of over 90% purity. 12

8. The process of treating petroleum oils containing sulfo-acid salts, which consists in removing said salts from the oil by sub-

- jecting the oil to the solvent action of glycerin of over 90% purity, accompanied by agitation and heat.
9. The process of treating oils which consists in subjecting the oil to the action of sulfuric acid and an alkali, and removing the impurities resulting from the acid and alkali treatment by subjecting the oil to the action of glycerin.
10. The process of treating oils, which consists in subjecting the oil to sulfuric acid and alkali of such strength and quantity as to produce a clear line of separation between the oil and the aqueous layer upon settling, separating the oil from said aqueous layer, and removing the impurities resulting from the acid and alkali treatment by subjecting the oil to the solvent action of glycerin.
11. The process of treating oils, which consists in subjecting the oil to sulfuric acid and alkali of such strength and quantity as to produce a clear line of separation between the oil and the aqueous layer upon settling, separating the oil from said aqueous layer, dehydrating the oil and removing the impurities resulting from the acid and alkali treatment by subjecting the oil to the solvent action of glycerin.
12. The process of treating oils, which consists in subjecting the oil to sulfuric acid and alkali of such strength and quantity as to produce a clear line of separation between the oil and the aqueous layer upon settling, separating the oil from said aqueous layer, dehydrating the oil and removing the impurities resulting from the acid and alkali treatment by subjecting the oil to the solvent action of glycerin substantially free from water.
13. The process of treating oils which consists in subjecting the oil to sulfuric acid and alkali of such strength and quantity as to produce a clear line of separation between the oil and the aqueous layer upon settling, separating the oil from said aqueous layer, dehydrating the oil and removing the impurities resulting from the acid and alkali treatment by subjecting the oil to the solvent action of the glycerin, washing the oil and filtering it.
14. The process of treating petroleum oils containing sulfo-acid salts, which consists in subjecting the said oil to the solvent action of glycerin, settling out the glycerin and the solution of sulfo-acid salts in glycerin, and washing and filtering the supernatant oil.
15. The process of treating petroleum oils containing sulfo-acid salts, which consists in subjecting the said oil to the solvent action of glycerin, settling out the glycerin and the solution of sulfo-acid salts in glycerin and recovering the glycerin.
16. The process of treating petroleum oils containing sulfo-acid salts, which consists in subjecting the said oil to the solvent action of glycerin, settling out the glycerin and the solution of sulfo-acid salts in glycerin and recovering the glycerin by distillation and evaporation.
17. The process of treating petroleum oils, which consists in subjecting the oil to strong sulfuric acid in proportion of about 37% by volume of the oil treated, then treating the oil with alkali of from 10° to 40° Baumé in amount of about 20% of the body of oil being treated, thereby producing a clear line of separation between the oil and the aqueous layer upon settling, and removing the impurities resulting from the acid and alkali treatment by subjecting oil to the solvent action of glycerin.
18. The process of treating petroleum oils, which consists in subjecting the oil to strong sulfuric acid in proportion of about 37% by volume of the oil treated, then treating the oil with alkali of from 10° to 40° Baumé in amount of about 20% of the body of oil being treated, thereby producing a clear line of separation between the oil and the aqueous layer upon settling, and removing the impurities resulting from the acid and alkali treatment by subjecting the oil to glycerin in amount from 5% to 10% by volume of the body of oil.
19. The process of treating petroleum oils, which consists in subjecting the oil to strong sulfuric acid in proportion of about 37% by volume of the oil treated, then treating the oil with alkali of from 10° to 40° Baumé in amount of about 20% of the body of oil being treated, thereby producing a clear line of separation between the oil and the aqueous layer upon settling, separating the oil from said aqueous layer, dehydrating the separated oil and removing the impurities resulting from the acid and alkali treatment by subjecting the oil to the solvent action of glycerin.
20. The process of treating petroleum oils, which consists in subjecting the oil to strong sulfuric acid in proportion of about 37% by volume of the oil treated, then treating the oil with alkali of from 10° to 40° Baumé in amount of about 20% of the body of oil being treated, thereby producing a clear line of separation between the oil and the aqueous layer upon settling, separating the oil from said aqueous layer, dehydrating the separated oil and removing the impurities resulting from the acid and alkali treatment by subjecting the oil to the solvent action of glycerin, which is practically water-free and in amount of from about 5% to about 10% by volume of the body of oil.
21. The process of treating petroleum oils, which consists in subjecting the oil to strong sulfuric acid in proportion of about 37% by

volume of the oil treated, then treating the oil with alkali of from 10° to 40° Baumé in amount of about 20% of the body of oil being treated, thereby producing a clear line 5 of separation between the oil and the aqueous layer upon settling, separating the oil from said aqueous layer, dehydrating the separated oil and removing the impurities resulting from the acid and alkali treatment by 10 subjecting the oil to the solvent action of

glycerin, which is practically water-free and in amount of about 8% by volume of the body of oil.

In testimony whereof I have hereunto signed my name in the presence of two sub- 15 scribing witnesses.
